UNITED STATES PATENT OFFICE.

GALT M. MELVEN, JOHN H. GROVE, JOSEPH J. LEITSCH, AND THEOPHILUS L. MELVEN, OF LOUISVILLE, KENTUCKY.

SMOKE-CONVEYER.

SPECIFICATION forming part of Letters Patent No. 663,917, dated December 18, 1900.

Application filed May 24, 1900. Serial No. 17,876. (No model.)

To all whom it may concern:

Be it known that we, GALT M. MELVEN, JOHN H. GROVE, JOSEPH J. LEITSCH, and THEOPHILUS L. MELVEN, citizens of the United States, residing at Louisville, in the county of Jefferson and State of Kentucky, have invented a new and useful Smoke-Conveyer, of which the following is a specification.

Our invention relates to a novel smoke-conveyer designed particularly for use in connection with railroad-trains.

One object in view is to provide a conductor or conveyer which will receive the smoke and gases from the stack of a locomotive and discharge them at the rear end of the train, the purpose of the device being to prevent the smoke and cinders from coming into contact with the cars to the annoyance of the passengers and the soiling of the car furnishings and finish.

A subordinate object is to provide for the unrestricted direct escape of the smoke from the top of the stack when the locomotive is at a standstill by means of a cap or valve located and arranged in a manner to permit its direct escape or to close the top of the stack in a manner to compel the smoke to pass therefrom into the conveyer and to admit a direct draft through said conveyer for the purpose of carrying the products of combustion therethrough.

To the accomplishment of these several objects the invention consists in the construction and arrangement of parts to be herein-after described and illustrated, and succinctly defined in the appended claims.

In the accompanying drawings, Figure 1 is an elevation of a locomotive equipped with our smoke-conveyer. Fig. 2 is a fragmentary perspective view of the contiguous portions of the conveyer and stack, showing the cap open and illustrating its closed position in dotted lines.

Referring to the numerals of reference employed to designate corresponding parts in the several views, 1 indicates a locomotive, and 2 a tender, coupled together in the ordinary manner and comprising a railway-train.

4 indicates the smoke-stack of a locomotive, and 5 a tubular smoke-conveyer, preferably of about the same diameter as the stack and

extending rearwardly from the upper end of the stack to the rear end of the train, where the products of combustion from the furnace of the engine are designed to be discharged. 55 The conveyer 5 is made up of a number of individual sections, one of which is preferably supported upon each vehicle by conveyer-supporting brackets 6, comprising a ring 7, encircling the conveyer-section adjacent to its 60 ends, and a pair of legs or standards 8, supporting the ring 7 and bolted or otherwise secured to the top of the vehicle. Suitable means for coupling the several conveyer-sections are necessarily employed, as shown. 65

At suitable points along the conveyer and preferably in each of the sections is provided a draft or ventilating opening 16, straddled by an angular ventilator 17, arranged to permit the ingress of a current of air serving to 70 aid in the propulsion of the products of combustion toward the rear end of the train and without permitting the escape of such products through the ventilator-opening.

The essential feature of our invention is 75 that arrangement at the juncture of the conveyer and smoke-stack which permits the direct escape of the smoke and gases from the latter under certain conditions and compels such products of combustion to be discharged 80 into and through the conveyer under certain other conditions.

In Figs. 1 and 2 of the drawings it will be seen that the front end of the conveyer—that is to say, that section which is carried by the 85 locomotive—is bent at right angles to form a thimble or sleeve 20, which is slipped over the upper end of the stack 4 to have a smoke-tight connection therewith. The upper front corner of the conveyer is cut away at an angle of about forty-five degrees to form an 90 opening 21, disposed angularly with respect to both the stack and conveyer and coextensive diametrically with both the stack and conveyer, so that when this opening is unobstructed the front end of the conveyer and the upper end of the stack will be entirely open. The purpose of this peculiar arrangement is to provide for the direct escape of the smoke and gases from the stack 4 when 100 the locomotive is at a standstill and the opening 21 is uncovered. Under ordinary condi-

- tions, however—that is to say, when the train is in motion—this opening 21 must be closed to prevent the exhaust from driving the smoke and cinders upwardly through the opening 5 and into contact with the cars. For this purpose we provide a cap or valve 22, preferably of convex circular form and hinged, as by a hinge 23, to the sleeve 20 of the conveyer at the lower edge of the opening 21.
- 10 Suitable means for actuating the cap or valve 22 and for retaining it in its opened and closed positions must be provided, and we prefer to employ a cap-actuating rod 24, pivotally connected to the cap and extended 15 rearwardly into the cab of the locomotive, within convenient reach of the engineer. In order to create a direct draft through the conveyer when the train is in motion, we provide the cap with an opening 25, located in a position to be coaxial with the conveyer when the cap 22 is closed, and from this opening we extend a draft-funnel 26, which when the cap is in its inclined closed position will be disposed coaxially with the conveyer. Thus 25 by the manipulation of the cap or valve 22 we are enabled to provide a direct opening at the upper end of the stack for the escape of the products of combustion or to completely close the upper end of the stack and to inaugurate 30 a draft through the conveyer from a point located beyond the front of the stack for the purpose of compelling the smoke and gases to be projected through the conveyer and discharged at the rear of the train.
- 35 From the foregoing it will be observed that we have produced a simple, ingenious, and effective arrangement for discharging the products of combustion from the fire-box of a locomotive at the rear of the train to prevent annoyance to the passengers and damage to the finish and furnishings of the cars; but while the present embodiment of our invention appears at this time to be preferable we do not desire to limit ourselves to the details defined, inasmuch as various changes, 45 modifications, and variations might be ef-

fected without departing from the spirit of the invention—as, for instance, the conveyer instead of being supported above the car might be conducted rearwardly under the 50 eaves at the sides of the car-roof or might, in fact, be located beneath the car, the essential characteristic of the apparatus being the conducting of the products of combustion to the rear of the train without obstructing the 55 effective draft necessary to the operation of the locomotive.

What we claim is—

1. The combination with a smoke-stack, of a conveyer extending at right angles thereto 60 and provided with an opening coaxial with both the stack and conveyer, a hinged cap arranged to close over the opening; a draft-funnel opening through the cap at a point coaxial with the conveyer when the cap is 65 closed and disposed at an angle to the cap to permit such coaxial relation, and means for actuating the cap.

2. The combination with the smoke-stack of a locomotive, of a conveyer extending at 70 right angles thereto and provided with an opening coaxial with both the stack and conveyer, a convex cap arranged to close over the opening and hinged at its lower edge, a draft-funnel opening through the cap at a 75 point coaxial with the conveyer when the cap is closed and disposed at an angle to the cap to permit said funnel to have coaxial relation with the conveyer when the cap is in its closed position, and a cap-actuating device designed 80 to effect the opening or closing of the cap from a point removed therefrom.

In testimony that we claim the foregoing as our own we have hereto affixed our signatures in the presence of two witnesses.

GALT M. MELVEN.
